9 Claims. (Cl. 103—123)

This invention relates to rotary pumps and motors and particularly relates to pumps and motors of the kind in which a rotor unit or a stator unit is shaped to provide two or more compartments which are, in effect, swept by one or more vanes which act between the rotor and stator units and slide in one of the units, leakage from one compartment to the or an adjacent compartment, along the space between the rotor and stator units, being limited by suitably chosen close clearances between the rotor and stator units at those parts.

It is obvious that the rotor and stator units should not undergo too much strain under the pressurised conditions in which the pump or motor is to operate since, otherwise, the clearances referred to would be increased and excessive leakage would occur; adequate limitation of leakage under operating conditions is normally secured by suitable dimensioning and/or by choice of materials to prevent undue strain and/or distortion under the maximum pressure conditions. The higher the pressure, and/or the greater the length of wall swept by the vanes in each compartment, the thicker, for instance, will the wall of the outer member (normally the stator) need to be. For very high pressures, however, if the same materials were to be used as for lower pressure operation, the wall would have to be made so thick that the overall size of the device would become inordinately great and possibly, for certain purposes, unmanageable. Even though materials of higher modulus were available, the increase in modulus could not be great and the materials would be far more costly and their use would probably be ruled out for economic reasons.

It is an object of the present invention to provide for reduction of minimum thickness of the outer of the units of such pumps or motors for a given operating pressure or, alternatively, to provide a means for enabling such devices to be designed to work under reasonable conditions of leakage at higher pressure, without the necessity for excessive increase of bulk or for inordinate increase in cost.

In accordance with the present invention, the outer unit (which will normally be the stator unit) of a pump or motor of the kind referred to, is arranged to be subjected to fluid pressurisation, and in this way radial swelling of the outer unit, under the operating pressure, will tend to be counteracted. As an example of putting the invention into effect, the wall thickness of the outer unit of an existing design of pump or motor could be retained at its minimum value while the operating pressure could be raised considerably by such subjection to pressurisation, the actual increase depending to an extent upon the degree of pressurisation effected. Conversely, yet on a similar basis, it could be arranged that the thickness of the normal outer unit of a known device for comparatively low pressure operation could be reduced for the same operating pressure. In an arrangement according to the invention, enveloping means needs to be provided, against which the pressurised fluid may react, and this may take the form of a simple annulus of suitable material; the limitation on radial strain of the enveloping means is not related to leakage clearances, but only to the elastic limit of the material of which it is formed and the required pressurisation.

The pressurisation effected may be to a fixed value, but it is probable that adjustable pressurisation may be of use in particular cases; in certain embodiments, the pressurisation may be equal to, or related to, the operating pressure of the pump or motor. It may be desirable to pressurise so as to cause radial contraction of the outer unit, to compensate for the radial contraction of the inner unit under operating pressure, and so maintain the close clearances between rotor and stator.

One embodiment of the invention will now be described by way of example with reference to the accompanying drawings of which FIGURE 1 is a part-sectional side elevation of a double-unit motor; FIGURE 2 is an elevation of one of the units indicating that each unit comprises six vanes acting between a cylindrical stator unit and the rotor unit that are arranged to co-operate to form eight fluid compartments; FIGURE 3 is a part-sectional half elevation of one of the units of the motor and FIGURE 4 is a part-sectional view at right-angles to the line A—A in FIGURE 1.

In the drawings, the stators 1 and 2 of the two parts are arranged to be clamped together by end manifolds with suitable bolts, and a sandwich piece 3 is arranged between them; dowels 4 are provided to spigot the stators 1 and the sandwich piece, tension in the bolts being, for example, such as to avoid leakage of fluid under maximum operating pressure conditions of the motor. The eight fluid compartments of each unit of the motor are formed between lobes of the contoured part 5 of the rotor, and such lobes are indicated at 6; the contoured part is fitted and keyed to the driving shaft 7 of the motor. The sandwich piece has a bore which clears this part of the shaft.

The sandwich piece is provided with eight plug units, 35 these fitting eight cut-outs 9 (FIGURES 1 and 4) which correspond in position with keyhole-shaped slots 11 in the stators, each slot 11 housing a sliding vane 12 and providing a space 10 behind each vane.

Supported within each cut-out 9 is a pivot 13 for a 40 rocker arm 14, the ends of which are arranged to bear upon the outer edges of the vanes 12 in both parts so that, when the motor is functioning, the inner edges of the vanes are biased into contact with the edge of the contoured part of the rotor. Initially, biasing pressure 45 is obtained from the force exerted on the pivot 13 by springs guided by plungers 15 which slide in bearings 17; once powered rotation is established, additional hydraulic biasing pressure is obtained from pressurised fluid which is bled from the high pressure compartment on one side 50 of each vane to the spaces 10 at the backs of the vanes. This bleed occurs naturally up the high pressure face of each vane, due to the attitude it adopts in its slot when under load.

On each side of each vane slot 11 are ports 19 and 20. 55 For clockwise rotation of the shaft, ports 19 are input (pressure) ports for pressurised fluid fed from supply passages 21 communicating with input manifold, and ports 20 are exhaust ports to exhaust the fluid from behind the vanes as the pressurised fluid reacts on the front of the vanes to rotate the rotor; for this clockwise rotation, the exhaust fluid is led through passages 22 to the outlet manifold. The rotor and vanes are omitted from FIGURE 2 for clarity. Interchange of fluid connections to the manifolds will reverse the rotation of the rotor.

60 The rotor of the other part of the motor is keyed to the shaft 7 so that its lobes and vanes are exactly oppositely positioned relative to those of the first part, a typical positioning being indicated in dotted outline relative to the vane and lobe on the line B—B of FIGURE 2, though in 65 actual practice, the vanes are in a common plane through the line B—B. The sandwich piece 3 is provided with aligned passages so that the pressure ports and exhaust 70

ports respectively of each part 5 are in communication with each other, and therefore with the respective input and exhaust manifold.

By reason of the relative displacement of the rotors referred to above, and appropriate shaping of the lobes, the combined volume of the portions of the compartments being swept at any instant by associated vanes remains substantially constant and the torque and speed of the motor remains substantially constant during each revolution, provided that there is a constant supply of fluid.

The stators 1, which are of comparatively light construction, would be subject to distortion under pressure of fluid in the various swept compartments, thereby leading to the clearances between the tops of the lobe portions of the rotors and the inner surfaces of the stators being increased in operation and, in consequence, leading to excessive leakage past the lobes. However, in order to avoid this, in accordance with the invention each stator is surrounded by a ring member 2, each being sealed to the sandwich piece 3 by an O-ring seal 23 and to the respective manifold by similar means.

The internal dimensions of the ring 2 are such that, while permitting easy tolerances for machining, the ring will readily fit over its associated stator, leaving a reasonable clearance 24. Passages 18 are provided in the sandwich piece and in the plug units in cut-outs 9 so that pressurised fluid that bleeds to the spaces 10 behind the vanes will communicate with the space 24 to pressurise it, substantially at the operating pressure of the actuating fluid of the motor.

This fluid pressure acting on the outside periphery of each stator by reaction with the pressure ring 2, more than balances the high pressure forces on its inside surface, and so causes an inner contraction of the stator to compensate for any contraction of the associated rotor, thereby preserving the clearances between rotors and stators. It will be seen that, even if the rings themselves expand, this is of no consequence to operation of the motor. A high degree of strain being acceptable therefore, the pressure rings may be highly stressed, so that they can usefully be made of stronger material than the stators and comparatively thinly in consequence. The overall size of the motor for high pressure operation may be appreciably smaller than if the stators themselves were to be of the thickness required to resist undue distortion under such operating pressures; thus the stator material may be a spheroidal graphite iron which has properties suitable to impart wear resistance to its surface, and the pressure rings may be suitably machined from a high tensile steel.

It will be observed that the pressure rings 2 need not be rigidly fixed to provide for uniformity of the clearance space 24, since the fluid pressure acting in this space will not be affected by its shape.

Alternatively, the space 24 may be pressurised from an independent source of pressure. For this purpose further O-ring, or like, seals would be required to be between each stator and the sandwich piece on one side and the appropriate manifold on the other; a suitable duct would need also to be provided, probably in each manifold, through which pressurised fluid could be led to the clearance spaces 24. The actual pressure required to minimise clearances between stator and rotor being related to precise form and strength of the stator under the operating pressure.

It will be appreciated that similar considerations would apply in the case of a pump.

I claim:

1. A rotary hydraulic device comprising a stator unit, a rotor unit, said rotor unit being arranged to cooperate with said stator unit to provide at least two compartments for hydraulic fluid, at least one vane member adapted to bridge the gap between said stator and rotor units and in effect to sweep said compartments as the rotor unit rotates, an enveloping member peripherally surrounding and spaced from the outer of said stator and rotor units

and arranged for substantially free movement relative to said stator unit in directions at right angles to the axis of rotation of the rotor unit, and means for supplying hydraulic fluid under pressure to the space between said enveloping member and the outer of said units to compensate for pressure within said outer unit.

5 2. A rotary hydraulic device as claimed in claim 1, wherein said rotor and stator units are made from material of comparatively low tensile strength and said enveloping member is made from material having high tensile strength.

10 3. A rotary hydraulic device as claimed in claim 2, wherein said rotor and stator units are of cast iron and said developing member is of high tensile steel.

15 4. A rotary hydraulic device comprising a stator unit and rotor unit combination, said stator unit surrounding said rotor unit, and said rotor unit being arranged to cooperate with said stator unit to provide at least two compartments for hydraulic fluid, at least one vane member adapted to bridge the gap between said stator and rotor units and in effect to sweep said compartments as the rotor unit rotates, a shaft for said rotor unit, an enveloping member surrounding said stator unit and rotor unit combination, end members arranged one on either side axially of said stator unit and rotor unit combination, means for securing said end members and said stator unit in rigid fluid-tight assembly, at least one of said end members having bearing means for rotatably supporting said rotor unit shaft, said enveloping member being arranged at least in part between said end members, and fluid pressure sealing means arranged between the sides of said enveloping member and said end members.

20 5. A rotary hydraulic device as claimed in claim 4, wherein said sealing means comprise O-ring members each contacting said enveloping member and one of said end members.

25 6. A rotary hydraulic device comprising at least one casing member, a stator unit rigid with and in fluid-tight connection with said casing member, a rotor unit, at least one rotor unit bearing in said casing member, said rotor unit being arranged to cooperate with said stator unit to provide at least two compartments for hydraulic fluid, at least one vane member adapted to bridge the gap between said stator and rotor units and in effect to sweep said compartments as the rotor unit rotates, said stator unit cooperating with said casing member to provide at least one fluid entry passage and at least one fluid outlet passage for said compartments, said entry passage and said outlet passage being on opposite sides of said vane member, an enveloping member peripherally surrounding and spaced from the outer of said stator and rotor units, and at least one sealing means on each side of said enveloping member between the enveloping member and the casing member, said sealing means being under the influence of forces substantially only in the direction of the axis of rotation of said rotor unit and said enveloping member being substantially free from restraint in directions at right angles to said axis, the arrangement being such that fluid contained by said sealing means within the space between the enveloping member and the outer of said units react against the outer of said units to compensate for pressure within said outer unit.

30 7. A rotary hydraulic device comprising a pair of rotor units, a shaft for said rotor units, a stator unit for each said rotor unit peripherally surrounding the rotor unit, a spacer member between said stator units, two end casing members, each said casing member having bearing means for said rotor unit shaft, clamping means clamping each of said stator units between a casing member and said spacer member in rigid fluid-tight assembly, one of said casing members having hydraulic fluid entry means and said other casing member having hydraulic fluid outlet means, fluid passages in each of said stator units communicating with said fluid entry means and said fluid

outlet means, each pair of rotor and stator units being arranged to cooperate to provide at least two compartments for fluid, at least one vane member for each said pair of units adapted to bridge the gap between the units of each pair and in effect to sweep the said compartments as the rotor unit rotates, said vane member being arranged between the fluid entry passage and the fluid outlet passage in the respective stator unit, an enveloping member peripherally surrounding and spaced from each stator unit and being arranged at least in part between one casing member and the spacer member, and at least one sealing means on each side of each said enveloping member, said sealing means being arranged between the enveloping member and the respective casing member and between the enveloping member and the spacer member, said sealing means being under the influence of forces substantially only in the direction of the axis of rotation of said shaft and each said enveloping member being thereby substantially free from restraint in directions at right angles to said axis, the arrangement being such that fluid contained by said sealing means within the space between each enveloping member and the respective stator unit reacts against said stator unit to compensate for pressure within said stator unit while leaving the enveloping member substantially free for movement in directions at right angles to said axis.

8. A rotary hydraulic device comprising two stator units and a rotor unit for each of said stator units, said rotor units being arranged to combine with the respective stator unit to provide at least two compartments for hydraulic fluid in each combination, at least one vane member in each combination, a vane slot in one unit of each said combination, said vane members being adapted to act to bridge the gaps between the respective two units in each combination and in effect to sweep the compartments in the same as each rotor unit rotates, a sandwich member between said two stator units, said sandwich

- member being provided with means for mechanically biasing said vane members against the rotor surface, manifold end means at each end of the device, said manifold means being clamped with the stator units and sandwich member between them, in rigid fluid tight assembly, enveloping means enveloping each said stator unit, said enveloping means being adapted to contain pressurising fluid to cause pressure to be exerted upon the outer surfaces of said stator units to counteract, at least in part, any tendency of said stator unit to swell under pressure of hydraulic fluid in said compartments, and pressure resisting sealing means between each said enveloping means and surfaces adjoining said enveloping means to assist in containing said pressurising fluid, said enveloping means being substantially free from restraint in directions at right angles to the axes of rotation of said rotor units.
9. A rotary hydraulic device as claimed in claim 8, wherein a passage is provided between said sandwich member and one of said stator units to provide access from said vane slot to the space between each said enveloping means and its associated stator unit, whereby said pressurising fluid may be derived from the hydraulic fluid in said compartments.
